UNITED STATES PATENT OFFICE.

JAMES A. TILDEN, OF HYDEPARK, MASSACHUSETTS, ASSIGNOR TO HERSEY MANUFACTURING COMPANY, OF SOUTH BOSTON, MASSACHUSETTS, A CORPORATION OF MAINE.

METER.

SPECIFICATION forming part of Letters Patent No. 729,701, dated June 2, 1903.

Application filed February 26, 1903. Serial No. 145,121. (No model.)

To all whom it may concern:

Be it known that I, JAMES A. TILDEN, a citizen of the United States, residing at Hyde-park, in the county of Norfolk and State of Massachusetts, have invented a new and useful Improvement in Meters, of which the following is a specification.

My invention relates to meters, and more particularly to those adapted for the measurement of fluids.

It consists in the features hereinafter described and more particularly claimed.

The accompanying drawing shows a meter in side elevation, parts being broken away, illustrating one embodiment of my invention.

To secure the best results from the registering mechanism of water and like fluid-meters, it is essential that they should be enclosed in a casing which is substantially air-tight, thus avoiding the oxidation of the lubricant and also excluding dirt and fluids, which clog and interfere with the proper operation. To effect this, the ordinary practice heretofore has been to continue the spindle which is geared to the measuring device through the usual stuffing-box in the meter-casing, then across a chamber having communication with the outer air, and through a stuffing-box in the bottom of the register-casing, where it has secured to it a pinion meshing with a gear upon the driven spindle of the register. This arrangement is objectionable, not only because of the difficulty of properly packing two openings through separate members about an integral spindle, but also because of the inconvenience of disassembling and reassembling the parts, particularly when the meter is in use. It is necessary after removing the register-casing to take off the pinion from the spindle and then draw the register-plate up over said spindle. As the person doing this is often unskilled, the spindle is liable to injury by bending, the restoring of the plate is troublesome, and the packing in the stuffing-box may become scored or displaced by the end of the spindle, so that a leak will result. To obviate these difficulties, the arrangement disclosed in my Patent No. 675,145, dated May 28, 1901, was devised in which a section is removed from

the spindle between the meter-casing and register-casing and a flexible connector comprising a pair of arms connected by a pin introduced. This does away with the necessity for care in alining the stuffing-boxes and permits ready longitudinal separation. This construction, however, is open to objections in that it introduces a number of additional elements augmenting the cost of construction, and it also increases the total height of the meter by the space necessary to introduce the connector between the glands of the two stuffing-boxes. To avoid these and other difficulties which may arise, I provide such a combination of parts as is illustrated in the drawing, in which—

The numeral 10 designates a meter-casing containing any suitable form of measuring mechanism which imparts rotation to a spindle 11, extending through a stuffing-box or other desired packing device 12, having the adjustable gland 13. Carried by the meter-casing about the spindle is a support 14, here shown as of cup shape and formed integrally with the casing. Upon its outer or supporting edge the cup is preferably formed with an inner circumferential groove 15, in which is seated the bottom plate 16 of the register R, having its upper face flush with the upper edge of the support. The register mechanism is covered by the casing 17, the lower annular edge of which extends over both the support and register-plate and is suitably secured to the former with a packing-ring 18, interposed to form a tight joint. The register-casing is so sealed as to be substantially air-tight, the posts 19, which rise from the bottom plate to support the top plate, being driven into their holes in the former, and the spindles 20 of the register-gearing 21 may be stepped in plugs 22, similarly driven in to give the proper thickness of material at the bearing-points without unduly increasing the weight of the plate. Through the bottom plate, out of alinement with the spindle 11, extends the driving-spindle 23 of the register mechanism, which is encircled by a stuffing-box 24, having an adjustable gland 25. The spindles 11 and 23 project by one another and carry co-acting connectors lying in a plane extending

laterally of the spindles and substantially at right angles thereto. These connectors are here shown as intermeshing gears 26 and 27, secured to the meter and register-spindles, 5 respectively, by set-screws 28. The gears are inclosed by the supporting-cup, so that they are largely protected from dirt, though the interior of the cup is rendered open to external conditions by holes 29 through the 10 walls thereof, preferably near the top of the meter-casing, through which any water leaking from said meter-casing about the spindle 11 may readily escape.

It will be evident that in addition to the 15 ordinary advantages possessed by the divided and doubly-packed spindle my present invention secures these with practically no increase in height or bulk of the meter, there being practically only the width of space 20 necessary between the two casings for the stuffing-boxes, that the register is removable for inspection and repair without danger of injury to the spindle or packing, that the plurality of projections or teeth of the gears 25 permits assembling without difficulty in bringing the parts into proper engagement, and that even such members as the comparatively coarse intermediate gears, which are not liable to injuriously clog or wear, are well 30 protected. Moreover, the sealing of the register-casing at its juncture with the support from the meter-casing is accomplished in a very simple and effective manner which secures the maximum economy of space.

35 Having thus described my invention, I claim—

1. The combination with a meter-casing and a register-casing each provided with a stuffing-box, of spindles projecting through the 40 stuffing-boxes and extending by one another, and connectors secured to the spindles and coacting in a plane extending laterally of said spindles.

2. The combination with a meter-casing and 45 a registering-casing each provided with a stuffing-box, of a spindle projecting from each casing through a stuffing-box, and intermesh-

ing gears carried by the spindles in close proximity to the stuffing-boxes.

3. The combination with a meter-casing and 50 a sealed register-casing, between which is a space open to external conditions, of a spindle projecting from each casing into the intermediate space and located out of alignment with its companion spindle, a packing 55 device about each spindle furnishing a substantially water-tight joint between the casings and the intermediate space, and coacting connectors carried by the spindles within the intermediate space and situated in close 60 proximity to the packing devices.

4. The combination with a meter-casing, of a register-casing containing gearing, a register-plate provided with openings, plugs closing the openings to render them substantially 65 water-tight and to furnish bearings for the register-gearing, and means for assembling the register-casing and register-plate to seal the casing against external conditions.

5. The combination with a meter-casing, of 70 a support carried thereby and provided at its supporting edge with a groove, a register-plate seated in the groove and provided with openings, gearing carried by the register-plate, plugs closing the openings to render 75 them substantially water-tight and to furnish bearings for the register-gearing, and a register-casing extending over the adjacent edges of the support and register-plate.

6. The combination with a meter-casing, of 80 a cup-shaped support formed thereon, a register-casing supported upon the edge of the cup, a stuffing-box projecting from each casing into the cup, a spindle extending through each stuffing-box, and intermeshing gears carried by the spindles within the cup.

Signed at Boston, in the county of Suffolk and State of Massachusetts, this 24th day of February, 1903.

JAMES A. TILDEN.
